UNITED STATES PATENT OFFICE.

SILAS R. OWEN, OF ST. JOSEPH, MISSOURI.

CUTTING APPARATUS FOR HARVESTING-MACHINES.

SPECIFICATION forming part of Letters Patent No. 323,880, dated August 4, 1885.

Application filed December 31, 1883. (No model.)

To all whom it may concern:

Be it known that I, SILAS R. OWEN, a citizen of the United States, residing at St. Joseph, in the county of Buchanan and State 5 of Missouri, have invented certain new and useful Improvements in Cutting Apparatus for Harvesting-Machines; and I do hereby declare the following to be a full, clear, and exact description of the invention, such as will 10 enable others skilled in the art to which it app pertains to make and use the same, reference being had to the accompanying drawings, and to the letters of reference marked thereon, which form a part of the specification.

15 The invention relates to improvements in cutting apparatus for harvesting-machines; and it consists in the construction, combination, and adaptation of parts, as will be hereinafter more fully set forth, and specifically 20 pointed out in the claim appended.

The main object of my invention is to improve devices of the character referred to, so as to reduce the strain and consequent wear and tear upon various parts thereof, and to secure 25 a lighter-draft machine without a reduction of cutting capacity. These objects I accomplish by the mechanism shown in the accompanying drawings, in which—

Figure 1 is a plan view of the endless cutting apparatus and its frame removed from the machine. Fig. 2 is a view of a side elevation of the same, partly in section. Fig. 3 is a sectional view taken on the lines $y-y$ of Fig. 1 and partly broken away. Fig. 4 is a 35 plan view of two of the cutting-teeth and their connecting-bars, and Fig. 5 is a view of a side elevation of the same. Fig. 6 is a plan view of my invention, showing the same applied to a mowing-machine. Fig. 7 is a front elevation 40 of the same, and Fig. 8 is a cross-sectional view taken on the lines $x-x$ of Fig. 6.

Referring by letter to the drawings, A indicates the frame of a mowing-machine, which may be of any ordinary or approved construction; and B, one of the driving and supporting wheels thereof, which is secured to the axle D. E is a bevel-gear, which is keyed on the said axle, and engages a smaller bevel-gear, H, which is fixed to one end of a shaft, F, which 45 is arranged at right angles to the shaft D, and is supported in said frame. The shaft F is

provided at its opposite or outer end with a chain-wheel, K.

V indicates an angular metallic plate or casting, which is secured to the frame A, as 55 shown, and is provided with downwardly curved lug-hangers T, which form a support for the cutting apparatus and frame carrying its operating mechanism. R indicates a metallic frame, to the lower horizontal portion of 60 which is secured the finger-bar b. In the vertical arms or branches of this frame is journaled a horizontal shaft, L, which is provided about midway its length with a fixed vertical bevel-gear, M, which is journaled to the 65 hanger-lugs V V by means of journal-boxes T, as shown. This frame R is also provided beneath the shaft L with a transverse bar, S, through which passes a short vertical shaft, f, carrying at its upper end a fixed bevel-pinion, 70 g, which engages with the bevel-gear M on the shaft. To the opposite or lower end of this vertical pinion-shaft f is secured a chain-wheel, C, and is arranged on the finger-bar b, so as to drive the endless cutter, as will be 75 presently explained.

It will be perceived that the shaft L is arranged parallel to the shaft F, and is provided at its outer end with a chain-wheel, P, by which, through the medium of an endless 80 chain, N, motion may be imparted to the cutting apparatus received from the gear on the driving-axle.

It will be readily seen that my improvements may be applied to any mower without 85 impairing its usefulness or altering its construction in any manner whatever, and the shaft L, as well as serving as a medium for transmitting motion from the mower to the cutting apparatus, serves as a hinge-joint 90 whereby the said cutting apparatus may be adjusted at various angles to the machine and adapt itself for uneven or undulated surfaces.

To attach the cutter to the machine the boxes T are first removed and the journals of 95 the shaft L placed in the lug-hangers, after which the boxes are replaced and firmly bolted again, as shown more fully in Fig. 8.

a represents a sectional jointed band, carrying cutting-sections b', which rotate upon 100 band-wheels or pulleys C C', which are journaled at each end of the finger-bar b. One

end of this finger-bar is provided with a central longitudinal slot, in which is arranged a rectangular slide, *e*, adapted to be moved in and out within the slot by means of a threaded 5 rod and thumb-nut, *e'*, the object being to regulate the tension of the jointed cutting band by moving the pulley *C'*, which is journaled in the said slide. This finger bar *b* is provided with a circumferential recess, *b''*, to partially 10 receive the cutting-sections and the flat bars connecting the same, whereby they may be kept perfectly straight and prevented from sagging during operation. *a'* indicates flat bars for connecting the cutter-sections. These 15 bars are provided at opposite ends with vertical circular apertures, and the alternate ends of the tangs of the cutters are also recessed to receive the bolt which connects the plates *a'*. The heels or tangs of the cutter-

sections are riveted between the plates *a'*, as 20 shown at *k*, and the said plates are connected at opposite ends by passing bolts or other suitable fastening devices through the apertures *h*.

Having thus described my invention, what I claim as new, and desire to secure by Letters 25 Patent, is—

In the improved connecting-gear, the combination of stirrup *R*, the cross-bar *S*, the shaft *L*, bevel-gear *M*, chain-wheel *P*, casting *V*, boxes *T*, chain-belt *N*, chain-wheel *K*, shaft 30 *F*, pinion *H*, and drive gear-wheel *E*, substantially as described, and for the purposes set forth.

SILAS R. OWEN.
